CLAIM

The ornamental design for a garment as shown and described.

DESCRIPTION

FIG. 1 is a front elevational view of a garment;

FIG. 2 is a rear elevational view thereof;

FIG. 3 is a front perspective view thereof;

FIG. 4 is a right side elevational view thereof;

FIG. 5 is a left side elevational view thereof; and,

FIG. 6 is a bottom perspective view thereof.

The broken lines within the claimed surfaces of the garment depict features of the article that form no part of the claimed design. The broken line outline of the partial human figure in FIGS. 1, 2, 4, and 5 assists in illustrating how the garment may appear when in a position of use, but forms no part of the claimed design. The appearance of any portion of the article between the symbolic break lines, shown in dash-dot-dash broken lines, forms no part of the claimed design.
